UNITED STATES PATENT OFFICE

JOSEPH N. GRANT, OF LOUISVILLE, KENTUCKY, ASSIGNOR TO THE GRANT STORES INC.,
A CORPORATION OF DELAWARE

SELF-SERVING STORE

Application filed March 12, 1928. Serial No. 260,962.

The present invention relates to self serving store structures of a type in which the customer selects and secures for himself the articles he desires to purchase, which articles 5 are then checked up by a cashier and wrapped for transportation from the store.

An object of the invention is to provide a structure of this character whereby occupants of vehicles and pedestrians may pass 10 in a predetermined path through the store and inspect and select the goods which they desire to purchase from display racks arranged adjacent the travel of such vehicles and pedestrians.

More particularly the present invention 15 comprises the construction of the display rack, which is mounted for rotation within convenient reach of either the pedestrian or the occupants of the vehicle and provided 20 with a series of trays arranged for movement with the rack and also providing operating means for the rack with control means arranged for manipulation by either the pedestrian or the occupants of the vehicle whereby 25 to move a desired tray into position for convenient reach whereby to inspect and remove the articles therefrom.

A still further object of the invention is to 30 provide an apparatus of this character of simple and practical construction, which is neat and attractive in appearance, relatively inexpensive to manufacture and maintain in operation, and otherwise well adapted to the purpose for which the same is intended.

Other objects and advantages reside in the 35 special construction, combination and arrangement of the various elements forming the invention, and in which:

In the drawings—

Figure 1 is a plan view of one form of store 40 structure embodying my invention,

Figure 2 is a longitudinal vertical sectional view through the store showing the battery of display racks in elevation,

Figure 3 is a transverse sectional view 45 through one side of the store illustrating the drive way for the vehicle,

Figure 4 is a side elevational view of one 50 of the display racks,

Figure 5 is an end elevational view thereof,

Figure 6 is a detail of the worm and gear connection for operating the rack,

Figure 7 is a perspective view of one of the display trays carried by the rack,

Figures 8 and 9 are details of the support 55 for rotatably mounting the rack,

Figure 10 is a plan view of a modified form of store structure, and

Figure 11 is a similar view of a further 60 modification thereof.

Referring to the drawings in detail, the invention embodies the provision of a store structure, of a type as disclosed in United States Letters Patent No. 1,633,886 and including a suitable building having side walls 65 5 with windows 6 and a roof structure 10, the whole enclosing a store space 13.

The pencil portion of this enclosed space, in the form of the invention as illustrated in Figure 1 of the drawing is provided with a 70 curbing 14 whereby to slightly elevate such central portion above the portion of the enclosed area about the walls of the store, and arranged upon this elevated portion, close to the edge of the curbing 14, and extending substantially completely thereabout is a 75 counter 15 forming a support for a battery of display racks indicated generally at 16.

Each of the racks 16 comprises a rack frame including a horizontally disposed 80 shaft 17 journalled for rotation at each end upon brackets 18 extending upwardly from the upper surface of the counter 15, each end of the shaft being provided with a spoke wheel 19 with a series of spaced parallel rods 85 20 extending between the outer edges thereof.

From each of the rods 20 is freely suspended a pair of tray hangers 21, having 90 their lower ends forked as indicated at 22 and attached to the opposite ends, adjacent the opposite sides of a tray 23.

By reason of the manner in which the trays 23 are freely suspended from the rods 20, the trays are approximately supported at a horizontal plane. At one end of the shaft 17 is arranged a worm 24 engaging a worm wheel 25 operated through a drive pinion 26 from an electric motor 27. A motor 27 is operatively 95 associated with each of the racks 16 and is 100

connected in an electric circuit for the operation of the motor, each motor being controlled by an electric switch 28 positioned on each side of the counter 15.

5 As clearly illustrated in Figure 4 of the drawings, the central portion of the counter 15, immediately beneath the rack, is arranged at a relatively lower horizontal plane of the upper portion of the counter in order to permit 10 the rotation of the rack without interference of the counter with the trays 23.

It will be apparent from the foregoing description that the rack 16 may be operated so as to move either of the trays 23 into a 15 position more convenient by a person disposed at either side of the counter 15. At the side of the counter adjacent the curbing 14 is constructed a vehicle driveway indicated at 30 of sufficient width to permit the 20 passage of two vehicles, and as clearly illustrated in Figure 3 one of the vehicles, shown at 31 may be driven over the driveway adjacent the curbing 14 whereby the trays of each of the racks will be disposed in convenient 25 position to the occupant of the vehicle.

As clearly illustrated in Figure 1 of the drawings, the drive way 30 is reached through an entrance 32 at one end of the store structure with a counter 33 arranged alongside the 30 inner edge of the entrance and upon which may be arranged a number of automobile running board attaching trays 34 adapted to be supported in a suitable manner to the running board of the vehicle for supporting a 35 market basket 35 so that as the vehicle passes by the trays 23 the occupant may take the articles therefrom and deposit the same within the basket.

The opposite end of the driveway 30 terminates in an exit 36 adjacent the inner side of 40 which is arranged a counter 37, at which may be stationed a cashier to receive payment for the articles selected by the occupant of the vehicle as the vehicle passes from the store and also to collect the baskets 35 and 45 baskets 34.

Pedestrians may also enter the center space 13 through the turnstile 38 for collecting articles from the inwardly disposed trays 23, exits for the pedestrians being provided 50 through a turnstile 39 disposed adjacent the counter 37.

At the rear end of the store structure, in the embodiment illustrated in Figure 1 of the drawings, may be arranged a display space 40 for the display of certain articles, or for storage purposes, and also a space 41 which may be arranged as a sales room for the sale of automobile accessories or the like.

60 The space at the end of the store between the store room 40 and sales room 41 may be arranged as a gas filling station 42 for the vehicles passing through the store.

The modified store structures illustrated in 65 Figures 10 and 11 in the drawings are de-

signed for use under conditions where the store is peculiarly arranged with respect to the street, the modification shown in Figure 10 representing the plan of the store wherein its opposite end placed on different streets and in which the driveway 43 may extend directly through the store from one street to the other.

70 In the modification shown by Figure 11 of the drawing the store is shown arranged at a corner of a pair of intersecting streets, the entrance 44 for the driveway 45 having access from one of the streets and the exit 46 having access to the other of said streets. In both such modified forms of invention 75 the counter 15 upon which the racks are arranged are disposed along the curbing 15 formed at one side of the driveway.

80 From the foregoing it is thought that the construction, operation and advantages of the herein described invention will be apparent to those skilled in the art. Without further description it will be understood that various changes in the size, shape, proportion and minor details of construction may 85 be resorted to without departing from the spirit or sacrificing any of the advantages of the invention.

90 It is obvious that my invention is susceptible to various changes and modifications in construction without departing from the spirit of the invention or the scope of the appended claims, and I accordingly claim all such forms of the device to which I am entitled.

95 Having thus described my invention, what I claim as new is:

1. In combination with a store of the character described having separate vehicle and 100 pedestrian passageways with a counter interposed therebetween, of a display rack rotatably supported upon said counter, said counter having its central portion immediately beneath said rack arranged at a relatively lower horizontal plane to the upper portion of the counter to permit rotation of the rack without interference with said counter, operating means for the rack and means accessible to either side of the counter for controlling the operation thereof.

105 2. In combination with a store of the character described in which separate vehicle and 110 pedestrian passageways are provided with a counter interposed therebetween, a plurality of display racks disposed upon the counter in end to end relation, said counter having its central portion arranged immediately beneath the rack at a relatively lower horizontal plane of the upper portion of the counter, a horizontally disposed shaft rotatably supported upon the counter for each of 115 said racks, each of said racks including a plurality of tray supporting rods, means for securing the same for rotation about a common axis in spaced relation from said shaft,

a tray freely suspended from each of said rods and arranged for movement therewith, operating means for the shaft, and means for controlling the operation thereof from a position at either side of said counter.

5 3. In combination with a store of the class described, in which separate vehicle and pedestrian passageways are provided with the counter interposed therebetween and a
10 battery of display racks rotatably supported upon the counter upon a horizontal axis, a plurality of trays suspended from said racks and movable about the axis of the racks, operating means for the rack, said means comprising electric motors having individual
15 operable connection with the respective racks, means accessible to either side of the counter for controlling said motors and said counters having their central portions imme-
20 diately beneath the rack arranged at a relatively lower horizontal plane of the upper portion of the counter in order to permit rotation of the respective racks without inter-ference of the counter with the trays.

25 In testimony whereof I affix my signature.

JOSEPH N. GRANT.
